PUNCH

Filed April 6, 1925

2 Sheets-Sheet 2

UNITED STATES PATENT OFFICE.

HEYMAN ROSENBERG, OF NEW YORK, N. Y.

PUNCH.

Application filed April 6, 1925. Serial No. 21,014.

To all whom it may concern:

Be it known that I, HEYMAN ROSENBERG, a citizen of the United States, and residing at New York, in the county of New York and State of New York, have invented certain new and useful Improvements in Punches; and I do hereby declare the following to be a full, clear, and exact description of the invention, such as will enable others skilled in the art to which it appertains to make and use the same.

This invention relates to improvements in punches of the type adapted to be operated by hand and anchored on a bench.

The object in view is to provide means for punching work of variable depths such as the canopies of chandeliers and the like, and a more detailed object is the easy, quick and effective adjustment of the die relative to the punch and relative to the support of the die and the adjustment of the die support relative to the punch support for facilitating operation on work of different depths.

With these and further objects in view as will in part hereinafter become apparent and in part be stated, the invention comprises certain novel constructions, combinations and arrangements of parts as subsequently specified and claimed.

In the accompanying drawings,—

Figure 1 is a view in side elevation of a punch embodying the features of the present invention shown adjusted for shallow work.

Figure 2 is a similar view of the same shown adjusted for deep work.

Figure 3 is a rear view of the parts as seen in Figure 1.

Figure 4 is an enlarged, detail, fragmentary, sectional elevation of the punch and die and contiguous parts with the deep work extension in place.

Figure 5 is a similar view with the die located for shallow work, the parts being seen on a still further enlarged scale.

Figure 6 is a front or end view of the die arbor and die detached on the same scale as Figure 5.

Figure 7 is a vertical, central section through the punch portion, parts being seen

in elevation and the parts being shown on the same scale as Figure 4.

Referring to the drawings by numerals, 1 indicates an appropriate base adapted for anchorage to a bench or other suitable support from which rises the standard 2 arched to form the overhanging arm 3 terminating in the sleeve 4 forming the punch head. The punch bar 5 is mounted to reciprocate vertically within the sleeve 4, and at its lower end carries the punch 6. The upper portion of the bar 5 is formed into a rack 7 meshing with a segmental gear 8 forming the inner end of an operating lever 9, which lever is pivotally carried by a pin 10. The upper portion of the arm 3 is grooved and formed with upstanding side plates 11, 11, through which the pin 10 extends and finds bearing and between which the lever 9 swings. A set screw 12 is threaded through an outstanding lug 13 on the forward portion of sleeve 4 and adapted to be adjusted to limit the forward or operating stroke of the lever 9. A bifurcated or other appropriate stripper 14 is carried at the lower end of the stem 15 which projects upwardly in a vertical bore 16 in the rear portion of the head or sleeve 4. A set screw 17 is threaded into engagement with the stem 15 for locking the stripper 14 in any desired adjusted position.

The standard 2 and arm 3 are preferably formed of a central web with marginal flanges, as clearly indicated in Figure 3 and seen in Figures 1 and 2, and the standard 2 has its web enlarged at two points and perforated to form sleeves 18, 18, spaced vertically apart, and each an exact duplicate of the other. Locking set screws 19, 19, are threaded through the sides of the sleeves 18 to lock therein the shank 20 of an arbor 21 outstanding forwardly for said shank. The shank 20 is cylindrical to snugly fit within either of the sleeves 18, and is adapted to be rigidly clamped into place by the action of the screws 19.

The arbor 21 is made up preferably of a main bar having a tapered fillet or web 22 beneath to insure adequate capacity. The outer or free end of the arbor 21 is formed with a vertical bore or opening 23 having

an annular offset shoulder 24 forming a seat for the parts to be mounted on the arbor. A set screw 25 is preferably provided as a means for locking the parts to the arbor seated on the shoulder 24. As best seen in Figure 5, a sleeve 26 is placed within the bore 23 resting on the shoulder 24 and locked by the set screw 25 when the arbor is intended for location for shallow work, as seen in Figure 1. The sleeve 26 is internally threaded and is adapted to be engaged by the threaded shank of a tubular die 27 proportioned and located to cooperate with and receive the punch 6. A set screw 28 is passed through a portion of the punch bar 5 to engage the shank of punch 6 and lock the punch in its operative position. A gauge 29 partly surrounds the arbor 21 and is carried by a rod 30 extending through a bore 31 in the standard 2 and clamped in position by a set screw 32 for facilitating accurate location of work to be operated upon by the punch 6 and the die 27.

An extension standard 33 is provided with a shank 34 of the same external diameter as the sleeve 26 for enabling introduction into the bore 23 and against the seat 24 when the sleeve 26 is removed, and the upper end portion of the standard 33 is provided with a bore or recess 35 of the same dimensions as that portion of the bore 23 into which the shank 34 extends, the bore 35 terminating in an annular seat or shoulder 36. The sleeve 26 is adapted to be introduced into the bore 35 to rest on the seat 36 and to be locked in position by a set screw 37 passing through a portion of the extension standard 33. The extension standard 33 is preferably tubular and the lower end of the shank of die 27 is provided with tool-receiving kerfs 38, so that a screw-driver or like tool may be introduced either through the lower end of the bore 23 alone or therethrough and throughout the length of the standard 33 to engage and locate the die 27 for adjustment or removal or final seating thereof.

When shallow work is to be operated upon, the parts are arranged as seen in Figure 1, and the canopy or other work to be operated upon is introduced between the punch 6 and die 27 incident to lifting of the punch bar by the rearward swinging of the handle 9 to the position seen in Figure 2. The work being proportionally located, the handle is swung forward again, and the rack 7 thus forced down to the punch operating position, the punch cutting through the material of the work and ejecting a disc through the bore of the die 27. It frequently happens that shallow work and deep work are required on the same piece of material, or that the same operator must operate on shallow work for a time and then finds it necessary to work on deep work for a time. When this occurs, it is not necessary

for the operator to go to some other punch as is now commonly the practice, but it is only necessary to loosen the upper sets of set screws 19 and withdraw the shank 20 from the upper sleeve 18 and to insert the same in the lower sleeve and tighten up the set screws 19 for the lower sleeve, and then to adjust the die 27 and the extension standard 33 when the parts are ready to operate on the deep work. The adjustment of the die and extension standard merely consists of loosening the set screw 25, when the parts are in the position seen in Figure 5, removing the sleeve 26 with the die 27 located therein, placing said sleeve in the bore 35, and clamping it therein with the set screw 37, and then introducing the shank 34 of extension standard 33 into the bore 23 and clamping it therein with the set screw 25. A canopy or hood or other deep work may then be applied over the extension standard and successfully operated upon in the same punching machine which just before was used for shallow work. A substantial saving is thus effected in the time of the operator and in the expense of equipment in accomplishing the work of two punches as now commonly practiced by the utilization of the single punch machine disclosed.

What is claimed is:—

1. In punches, the combination of a standard and arm, the standard having a plurality of shank-receiving sleeves spaced apart vertically, a punch bar reciprocally carried by the arm, means for actuating the punch bar, an arbor having a shank proportioned to fit and be sustained by either of the sleeves, the arbor having a die-receiving opening, and an extension standard having a die-receiving opening at one end and a shank at the other proportioned to and mounted in the die-receiving opening of the arbor.

2. In punches, the combination of a standard and arm, the standard having a plurality of shank-receiving sleeves spaced apart vertically, a punch bar reciprocally carried by the arm, a punch carried by said bar, means for actuating the punch bar, an arbor having a shank proportioned to fit and be sustained by either of the sleeves, the arbor having a die-receiving opening, and an extension standard having a similar die-receiving opening at one end and a shank at the other mounted in the die-receiving opening of the arbor and sustained thereby, the extension standard being tubular.

3. In punches, the combination of a standard and arm, the standard having a plurality of shank-receiving sleeves spaced apart vertically, a punch bar reciprocally carried by the arm, a punch carried by said bar, means for actuating the punch bar, an arbor having a shank proportioned to fit and be sustained by either of the sleeves, the arbor

having a die-receiving opening therethrough formed with a shoulder, a sleeve adapted to fit within said opening and rest on said shoulder, a die detachably carried by said sleeve, an extension standard having an opening proportioned to receive said die-carrying sleeve at one end and a shank at the other end having the same proportions

of the die-carrying sleeve and mounted in the die-receiving opening of the arbor, the extension standard being tubular and the lower end portion of the die being adapted to receive an operating tool.

In testimony whereof I affix my signature.

HEYMAN ROSENBERG.
